UNITED STATES PATENT OFFICE

FRANK J. SEABOLT, OF SCHENECTADY, NEW YORK, ASSIGNOR, BY DIRECT AND MESNE ASSIGNMENTS, TO THE PHONOGRAPH COMPANY, A CORPORATION OF DELAWARE

PHONOGRAPH

Application filed August 9, 1923. Serial No. 656,570.

My invention relates to improvements in phonographs and the like and has for its object the provision of improved means whereby a plurality of records of assorted sizes may be played automatically in succession. In my previous Patents Nos. 1,622,814 and 1,623,559 I have employed an arm pivoted to move in a horizontal plane for shifting the records to and from playing position on the turntable. This arm is provided at its free end with a pivoted pin in a vertical position which engages the center hole in the record to shift the records by sliding them along the table. The arm is turned on its pivot by an electric motor energized when the end of a record is reached and the tone arm is turned back to the proper position for the new record by electrically controlled means.

My present invention in one aspect is in the nature of an improvement upon these earlier devices, one of the important improvements consisting in the substitution of a straight line movement of the record shifting pin for the arcuate movement of the prior devices. This provides a better mechanical arrangement and also makes possible a more convenient shape for the cabinet. Many of the operations which were carried out electrically in the earlier forms I have now worked out mechanically with the result that a simpler device as a whole is provided. Various other important features of my invention will appear in the course of the following specification, in which I have disclosed my invention embodied in concrete form for purposes of illustration.

In the accompanying drawings illustrating my invention in one desirable form Fig. 1 is a perspective view showing the main elements of my phonograph, certain parts being broken away and others somewhat enlarged to clarify the mode of operation. Fig. 2 is a plan view of the phonograph as a whole. Fig. 3 is a detail partly broken away of the record shifting bridge; Fig. 4 is a section on line 4-4 of Fig. 3; Fig. 5 is an elevation of the phonograph as a whole, Figs. 6 and 7 are details of the needle lifting device; Fig. 8 is a diagram of the circuit connec-

tions; Fig. 9 is an enlarged view of the arm shifting mechanism and Fig. 10 is a detail of the record magazine.

Referring first to Fig. 2, it will be seen that the location of turntable 10 is at about the center of the cabinet 11, the usual tone arm 12 being located as shown. To the left of the turntable is the magazine for containing unplayd records and symmetrically arranged at the right of the turntable is the receiving table in the nature of a trapdoor device 13, which deposits the played records into the receptacle below from which they may be recovered through door 13'. Two endless parallel link belts 14 and 15, one on each side of the turntable and connected by a bridge 16, form the record shifting means. The bridge is shown in detail in Figs. 3 and 4. It consists of a bar 17 secured to the link belts so as to move in a horizontal plane always parallel with itself. The record shifting pin 18 is pivoted at 18' to a supplementary arm 19 pivoted at 20 so as to oscillate in a plane perpendicular to the arm 19. This pin passes through the bridge and enters the center hole in the record. The arm 19 has a limited movement on its pivot between the spacer 21 and the knurled head 22 there being provided a knob 23 for lifting the pin out of the hole in the record to facilitate the manual removal and insertion of records as hereinafter pointed out. The pin 18 normally assumes a vertical position and is free to move on its pivot in one direction from the vertical, i. e., to the right in Fig. 4 but is restrained from movement in the opposite direction by the projection 24 on the pin. As shown in Fig. 2, a record is being played and the pin 18 is projecting into the hole in the record at the center of the turntable.

When the end of a record is reached a small electric motor 25 is energized to carry the bridge to the right (Fig. 2) and since the pin 18 is projecting into the hole in the record and the pin can not move to the left on its pivot, the record is slid across the turntable and onto the table 13. When the bridge has moved to the right far enough to carry the record to about the middle of table 100

13, which is held in horizontal position by the pivoted detents 26 spring pressed to the position shown in Fig. 2, by springs 26' the table is released and, since the table is pivoted at 27 and the greater part of the record is to the left of the pivot, it turns on its pivot as shown in dotted lines in Fig. 5 and deposits the record below. The detents are moved to release the table by projections 28 which engage the detents at the right of their pivots just before the center of the record coincides with the center of the table, and continues to hold the detent released as the bridge and record move farther. As soon 10 therefore as the left hand edge of the record passes the edge of the opening which is closed by the table 13, the latter tilts, and the record slides down as shown in Fig. 5, into engagement with the stack of records below, 15 20 the right hand edge of the record forcing the table, which is nearly counterbalanced, out of the way. When the record has cleared the table, the latter returns to horizontal position due to its being slightly over-counterbalanced at 29. As shown a wall or partition 30 is located so that the left hand edges of the records engage it. This all happens before the detents are released by the return of the bridge. When therefore, the detents 25 30 are released, the table is in horizontal position and will be held there by the detents.

As the bridge 16 moves to the left after the record is deposited as above described, it moves across the turntable, the pin 18, of course, clearing the table, and to the extreme left until the bridge is substantially over the center of the record 31 in the magazine at the left. This record as hereinafter pointed out, is above the surface of the turntable and 35 40 45 that of the stationary platform surrounding the turntable, the bottom surface of the record being flush with the surface of the surrounding platform. When the pin 18 engages the edge of the record 31 it turns easily on its pivot and then glides lightly over the surface of the record until it drops into the center hole in the record. At this point, the movement of the bridge to the left ceases and reverse movement is begun, whereupon the 50 55 60 pin 18 which is now restrained from moving beyond the vertical position, carries the record with it to the center of the turntable. The bridge 16 is now in its starting position but a new record is below it in playing position upon the turntable. This in general, is the sequence of operations. I shall now describe the mechanism whereby these operations are brought about.

Referring to Fig. 2, it will be seen that the 60 tone arm 12 is provided with a projection 32, which engages a pivoted switch arm 33 and turns it on its pivot into engagement with its contact 34, when, the end of the record having been reached, the tone arm is moved 65 quickly in toward the center of the record by

spiral groove 35. The closing of this switch energizes the electric motor 25 through connections hereinafter described. The driving connections between the motor 25 and the link belts 14 and 15 will best be understood by reference to Fig. 1. The motor drives through worm gearing 36 the ring gear 37 mounted on and secured to a shaft 38. At the center of the ring gear and secured to the shaft 38 is a mutilated spur gear 39. This ring gear 75 and the spur gear are driven in a counter-clockwise direction looking at Fig. 1, there being teeth at two places 40 and 41 on the gear 39 and at one place 42 on the ring gear. On the lower edge of the gear, at 42' are a few 80 teeth which drive the shaft 43 to lift the needle as hereinafter described. A gear 44 is located between the gear 39 and the ring gear 37 so as to be engaged and turned alternately by the teeth on the gear 39 and on the ring gear 85 and thereby reverse the direction rotation of the gear 44. Bevel gearing 45, driven by gear 44 operates shaft 46, to which are secured the sprocket wheels 47 driving the sprocket chains. These chains may have under them narrow strips 47' to prevent them from sagging. The motor 25, therefore, being engaged, turns the ring gear 37 and gear 39 in a counter-clockwise direction. The initial movement of the gear 37 merely turns 90 shaft 43, since the gear 44 is not engaged by any teeth until shaft 43 is turned and the needle lifted. When this is completed teeth 41 on the gear 39 mesh with the teeth of gear 44 and turn this gear in a clockwise direction, thereby turning sprocket wheels 47 in a clockwise direction (looking at Fig. 1). The bridge 16 therefore moves to the right (Fig. 2) as above described. When the bridge reaches approximately the center of the table 100 105 110 115 120 125 130 135 140 145 150 155 160 165 170 175 180 185 190 195 200 205 210 215 220 225 230 235 240 245 250 255 260 265 thereby lifts the needle. This is shown in my previous Patent No. 1,622,814 above referred to. The arrangement of these two cooperating parts is shown in Figs. 6 and 7. One part 59 is secured to shaft 55, while the other part 60 is pivoted to part 59 as shown. The flexible member 57 is secured to part 60 at 61. A switch 62 is engaged by the part 60 on the opposite side of pivot from connection 61 of the flexible member. A stop 63 on part 60 limits the relative movement of the two parts. When the shaft 55 turns and with it the part 59, if there is a pull on flexible member 57, which will be the case if the flexible member and its connections are intact so that the weight of the reproducer is on the flexible member, the two parts will move as a unit to the position shown in dotted lines in Fig. 6, thereby operating the switch 62 to closed position. If, however, there is no pull on the flexible member, the part 59 will turn with the shaft, but the part 60 will be restrained by the switch and forced to turn on its pivot as shown in Fig. 7. The switch 62 will therefore not be closed. When the needle is lifted it will be held in that position by spring pressed latch 64. This latch will be tripped when the end of the cycle is reached by the rod 64' operated by cam 65 on shaft 38. When the latch is tripped, the reproducer will drop under the retardation of dashpot 66 until the needle strikes the record and the flexible member is relaxed.

The needle having now been lifted, the bridge starts to move to the right and carry with it the record from the turntable. The tone arm is likewise turned back toward the starting position by the following instrumentalities. A cam 67 is secured to the upper end of shaft 38 and rotates at all times with it. Cooperating with the cam is a jointed rod 68 which is moved longitudinally in guides 69, each end being provided with an anti-friction roller. As the cam turns in a counter-clockwise direction (Fig. 2) it forces the rod 68 outward to the left against the light spring 70, the free end of the rod engaging a projection 71 on the tone arm and gradually forcing the needle toward the outer edge of the turntable. This movement is accomplished very slowly, and may not begin until the cycle of record shifting operations is well under way. As shown, no movement of the tone arm will take place until about the middle of the cycle; i. e., when the bridge is passing to the left over the turntable. The amount which the tone arm is turned back will depend upon the diameter of the record 31 which is to be placed on the table. To accomplish this, I have provided a lever 72 pivoted at 73, one end of which is provided with an anti-friction roller 74 to be engaged by the on-coming record, while the other end is provided with two stops 75 and 76, either one of which is engaged by projection 71, de-

pending upon the diameter of the on-coming record. If this record is of small diameter, as for instance, a ten-inch record, the roller 74 will not be engaged by the record, and hence the lever 72 will not be moved from the position shown in Fig. 2. Stop 75 will therefore be engaged by the projection 71 on the tone arm and stop the tone arm at the position corresponding with the proper starting position of the needle for a ten-inch record. After the projection strikes the stop, springs 68' will yield so as to allow the inner half of the rod 68 to be moved by the cam. When the on-coming record is a twelve-inch record, the record engages the roller 74 and moves it so that the stop 75 will be out of the path of the projection 71 and stop 76 will take its place. The tone arm will now be moved until projection 71 strikes stop 76, which will correspond with the starting position of the needle on a twelve-inch record. When the lever 72 is moved to this position, it is latched there by latch 77 until, during the next cycle, a lug 78 moving to the left, trips the latch and permits the lever 72 which is spring pressed, to return to its original position. The reason for latching the lever in the twelve-inch position is to provide for a repeating of the record, in which case the record shifting mechanism does not operate, as hereinafter pointed out. In order to slightly retard the tone arm and steady its motion while being turned back, I provide a brake 76' on the tone arm which is operated by rod 68 through pivoted lever 77'. During the playing of a record the brake will be entirely released.

The starting lever of the phonograph is shown at 79. In this case it is nothing more than a switch with a single contact for starting the electrically driven phonograph. As shown in Fig. 2, the operation of this lever performs three other functions. First, when the starting lever is moved to "off" position, a roller 80 carried by it, engages lever 72 and pushes it outward so that stop 76 is in operative position for stopping the tone arm. This happens, of course, only in case, when the starting lever is moved to "off" position, the lever 72 was in position for stopping on a small record. In fact, the lever 72 may be pushed further by the roller 80 upon stopping so that neither stop 75 nor 76 will interfere with the movement of the tone arm. The purpose of all this is to facilitate manual operation of the phonograph, that is to say, a record of either size may be placed directly on to the turntable manually and the tone arm will be free to move to any position (the machine being stopped). Second, when the starting lever is moved to "off" position, the latch 77 is tripped. This is accomplished by a link 78' pivoted to the end of the starting lever. The opposite end of this link is provided with a slot engaging a pin in the latch. When the starting lever is

moved to "off" position, it therefore pulls the latch out of latching position and holds it there. As the starting lever moves farther, the roller 80 forces the lever 72 outward as above described. Upon re-starting, the lever 72 will move back to its lower-most position corresponding with the position of the lever for a ten-inch record, before the latch is released. The purpose of thus insuring that the stop will always be in the ten-inch record position upon starting is that in case the operator places a ten-inch record upon the turntable, starts the machine and then throws the repeat lever (as hereinafter described) the needle will not be carried off the record as would be the case if the twelve-inch stop were set. In this case the needle will be carried back on the twelve-inch record to the ten-inch position and dropped. This machine is not intended to repeat the record which is manually placed on the turntable since there is no way of automatically setting the stop for a manually placed record. In case, however, an attempt is made to repeat this record no harm will be done since the needle cannot be carried off the record. The slot in the link permits the latch to operate in its normal way as above described. Upon starting of the machine the lever 72 will return to the position which it occupied before the machine was stopped. Third, the movement of the starting lever to "off" position places a barrier 81 across the path of switch 33. The purpose of this is to prevent the accidental or careless closing of switch 33 by the moving of the tone arm inward toward the center of the turntable when the machine is stopped. The closing of switch 33 would start motor 25, which of course should not happen while the starting lever of the phonograph is in "off" position. The starting lever likewise has attached to it a switch 82 (see Fig. 8) the purpose of which will hereinafter appear.

In order to make it possible to repeat any record, I simply throw the record shifting mechanism out of operation by lifting the gear 44 out of meshing position. For this purpose I mount the gear 44 on a spline and lift it along its shaft by means of the lever 83. This may be done at any time during the playing of a record. The effect will be that when the end of the record is reached, the motor 25 will be energized as usual, with the result that the needle will be lifted and the shaft 38 turned. This will operate cam 67 and turn the tone arm back the same distance that it did on its first operation, since the position of the stop lever 72 is not changed. The record shifting mechanism is, however, stationary, so that the played record will remain in place but the needle will be lifted, turned back to proper position and dropped. When the repeating lever is restored, either manually or automatically,

after one or more repetitions, the automatic operation will go on as before.

No attempt has been made to describe in detail the construction of the magazine on the left for containing the unplayed records. This construction may be and, as shown, is identical with that fully described in my earlier patents, particularly Patent No. 1,622,814. For present purposes it is sufficient to say that the magazine contains a number of records of assorted sizes in contact with each other with their centers in vertical alignment and pressed upward by a spring against the cover 84 pivoted at 84' and held down by the member 85, the top record having its bottom surface flush with the top of the surrounding table and with the surface of the turntable. When the top record is removed, the stack of records moves up so that the next succeeding one takes its place. When the last record is removed two switches 82 and 85 (Fig. 8) are opened, for purposes which will be now described.

In Fig. 8 I have shown a diagram of the electrical connections of my device. Referring to this figure, 86 represents as a whole, the phonograph, the turntable of which is in the center of Figs. 1, 2 and 5. As shown, this is an electrically driven phonograph, which may be of the well-known type now on the market, such as that shown in Patent No. 1,240,711 to C. I. Hall, dated Dec. 18, 1917. It is started and stopped by the operation of switch 79. The tone arm 12, when the end of a record is reached operates switch 33 from its normal position in engagement with contact 87, to which it is spring pressed into engagement with contact 34. Two pairs of slip rings 88-88' and 89-89', are mounted on shaft 38 and consequently are driven by the motor. With the parts at rest, slip rings 89-89' form a conducting path for current but slip rings 88-88' do not. The brush on slip ring 88 is on a dead segment while the brush of ring 89 is on a live or conducting segment. There being records in the magazine, switches 82 and 85 are closed. When therefore the end of a record is reached, the circuit of motor 25 will be closed as follows; from the positive side of the line through contact 34, switch 85, motor 25, slip rings 89-89' and back to the negative side of the line. The motor now starts and lifts the needle and in doing so closes switch 62. If, for any reason, as for instance, the breaking of the flexible connection 57, the needle is not lifted, then the switch 62 will not be closed, and the motor will be stopped before the record shifting mechanism starts because the brush on slip ring 89 passes off the conducting segment when the needle lifting movement is completed and before the record shifting mechanism starts. The switch 62 being closed, the circuit is now through it instead of through

the slip rings 89—89' and the motor will continue to operate until the cycle is completed. As soon as the tone arm starts to move back, the switch 33 will be moved back by its spring into engagement with contact 87 and will open the circuit, but, in the meantime, the brush of slip ring 88 has moved off its dead segment and on to the conducting portion. Circuit will now be through these slip rings 88—88', motor 25 and switch 62. The slip rings are so proportioned and designed that when the motor has rotated sufficiently to complete the cycle, and this will be when the ring gear and shaft 38 have made substantially one revolution, the brush of slip ring 88 will again pass on to its dead segment and the brush of slip ring 89 will pass on to its conducting segment. The switch 33 now being open, the motor stops. This operation will continue so long as there are any records in the magazine. When the last record is drawn from the magazine, switches 82 and 85 open as shown in Fig. 10. These magazine switches are operated in the same manner as the magazine switch shown in Fig. 11 of my previous Patent No. 1,622,814 except that there are two switches which are open instead of one which is closed when the last record is drawn from the magazine. The two switches and the manner in which they are opened are shown in present Fig. 10 of this application. This, however, will not stop either the phonograph or the motor 36. The latter can only be stopped by the completion of the pre-determined number of revolutions of the motor shaft—or by the dropping of the needle. The phonograph 86 will not stop because the switch 82 has a parallel circuit around it through switch 33 and contact 87. The last record will therefore be shifted into place, the needle dropped and the record played. When the end of this last record is reached, switch 33 will be moved off contact 87 and onto contact 34. This will stop phonograph 86 because magazine switch 82 is open and motor 25 cannot start because magazine switch 85 is open.

The operation of my device will now be clear. Records of assorted sizes are placed in the magazine and a record placed on the turntable. The phonograph is then started in the usual way by moving the starting lever to "on" position and placing the needle onto the record. When the end of a record is reached the record shifting mechanism operates as above described and the records in the magazine are played consecutively and deposited in the receptacle at the right. If it is desired to repeat a record the repeat lever is thrown and, upon the restoration of the lever, the automatic operation continues. When the last record has been drawn from the magazine and played, the phonograph and, of course, the entire mechanism stops. Practically, any number of records may thus

be played successively and automatically or the machine may be used as an ordinary non-automatic phonograph.

While I have described my invention as embodied in concrete form for purposes of illustration it should be understood that I do not limit my invention thereto since various modifications thereof will suggest themselves to those skilled in the art without departing from the spirit of my invention, the scope of which is set forth in the annexed claims.

I claim:

1. The combination with a phonograph or the like and a magazine of records adjacent thereto of a member movable in a straight line between the magazine and the turntable and having a part which enters the center hole of a record, means for reproducing a record and means whereby when the end of a record is reached said member is moved to engage the center hole of a record in the magazine and shift it to the turntable. 80

2. The combination with a phonograph or the like and a magazine of records adjacent thereto, of a member mounted beside the magazine and turntable and movable in a straight line therebetween, said member extending in to the center of the record and being provided with a part which enters the center hole of a record, means for reproducing a record and means whereby when the end of a record is reached said member is moved to engage the center hole of a record in the magazine and shift it to the turntable. 90

3. The combination with a phonograph or the like and a magazine of records adjacent thereto of a receptacle for played records below the level of the turntable a member normally closing the receptacle and movable so that the played record when placed upon the member will slide down into the receptacle and means for shifting a new record from the magazine to the turntable to replace it. 100

4. The combination with a phonograph or the like, and a magazine of records adjacent thereto, of a receptacle for played records below the level of the turntable, a closure for said receptacle arranged to receive a record and movable to permit the record to slide down into the receptacle and means for shifting a new record from the magazine to the turntable to replace it. 115

5. The combination with a phonograph or the like including a turntable, a magazine of records on one side thereof and a receptacle for played records on the opposite side all in a straight line, of a carrier movable in two directions on each side thereof and parallel therewith, a bridge connected to said carriers normally at the center of the turntable and a projection therefrom extending into the center hole of a record on the turntable pivoted to move the record when moved in 120

one direction and to glide over the record when moved in the opposite direction.

6. The combination with a phonograph or the like and a magazine of records adjacent thereto of a receptacle for played records adjacent the turntable, a closure therefor, and means for shifting a played record from the turntable to the closure of the receptacle and replacing it by a new record from the magazine said closure being movable so that the played record will slide down into the receptacle.

7. The combination with a phonograph or the like including a turntable and means for lifting the needle thereof, of receptacles for the played and unplayed records respectively one on each side of the turntable and a record shifting mechanism for shifting successive records from one receptacle to the turntable and from the turntable to the other receptacle, said mechanism moving beneath the needle when the latter is lifted.

8. The combination with the turntable of a phonograph including reproducing means, a magazine for unplayed records and a receptacle for played records all arranged in a straight line, of a record shifting member spanning the same transversely, means for moving said member parallel with said line when the end of a played record is reached and means associated with said member for removing successive played records to the receptacle and successive unplayed records from the magazine to the turntable.

9. The combination with a phonograph or the like and a magazine of records adjacent thereto, of a receptacle for played records adjacent the turntable, a tilting cover for the receptacle normally in position to receive a played record as it comes from the turntable, means for shifting successive played records from the turntable to the cover and new records from the magazine to replace them so that the played record will slide down into the receptacle.

10. The combination with a phonograph or the like including reproducing means and a magazine of records adjacent thereto, of a bridge normally spanning a record on the turntable having a projection which enters the center hole of the record, said projection being movable whereby when the end of a record is reached the played record is removed from the table and the bridge moves over the magazine, engages the center hole of a record and moves the record to central position on the turntable.

11. The combination with a phonograph or the like of a stack of records of different diameters and a receptacle for played records adjacent the turntable, a pivoted record support normally in horizontal position adjacent the turntable, means whereby when a record of any diameter on the turntable is completed it is caused to rest upon the

support which thereafter turns on its pivot to cause the record to slide into the receptacle and a new record of any diameter shifted from the stack to replace it.

12. The combination with a phonograph or the like of a stack of unplayed records of different diameters adjacent the turntable thereof, a record support normally in a horizontal position and means whereby as successive records of different diameters on the turntable are completed they are caused to rest upon the support which thereafter moves from the horizontal position to cause the records to form a stack adjacent the table and unplayed records are shifted from the stack to replace them.

13. The combination with a phonograph cabinet and a turntable and reproducer mounted in the upper portion thereof, of a receptacle for played records within the cabinet and below the level of the turntable, an opening in the top of the cabinet for admitting a record to the receptacle, means whereby when a record on the turntable is completed it is automatically turned from the horizontal position and caused to slide through the opening into the receptacle and a door at the side of the cabinet through which the played records are removed.

14. The combination with a phonograph or the like including reproducing means and a magazine of records adjacent thereto, of a receptacle for played records below the level of the turntable, a pivoted record support normally in horizontal position adjacent the turntable, and whereby when a record on the turntable is completed it is caused to rest upon the support which automatically turns on its pivot to cause the record to slide into the receptacle and a new record is moved from the magazine to replace it.

15. The combination with a phonograph or the like and a magazine of records adjacent thereto, of a receptacle for played records below the level of the table, a record support adjacent said receptacle and arranged to support a played record, said support being arranged to tilt to cause a record to slide downward into the receptacle and means for shifting a new record from the magazine to the turntable to replace it.

16. The combination with a phonograph or the like and a receptacle for played records below the level of the turntable, of a movable record support adjacent the turntable and means for moving the played record from the turntable to the support to rest thereon, the said support being thereafter moved to an inclined position by the weight of the record to cause the played record to slide downward into the receptacle.

17. The combination with a phonograph or the like including reproducing means and a magazine of records adjacent thereto, of a receptacle for played records below the level

of the turntable, a record support having a horizontal position and an inclined position, and means whereby when a record on the turntable is completed it is caused to rest on the support in its horizontal position said support being movable to its inclined position to cause the record to slide into the receptacle and a new record is shifted from the magazine to replace it.

10 18. The combination with a phonograph turntable and reproducer of a magazine for records adjacent the turntable, a receptacle for played records below the level of the turntable, a record shifting member normally at the turntable, means whereby when a record is completed the shifting member is automatically operated to first remove the played record from the turntable and then place a record from the magazine upon the turntable 15 to replace it and means whereby the played record after leaving the turntable is turned sufficiently from the horizontal to cause it to slide downwardly into the receptacle.

19. The combination with a phonograph turntable and reproducer, of a magazine for records adjacent thereto, a receptacle for played records below the level of the turntable, a record shifting member reciprocating above the level of the turntable between the 25 magazine and the turntable and above the receptacle, means whereby when a record is completed the shifting member is operated to move the played record from the turntable to a position above the receptacle and then place a record on the turntable to replace it and means whereby during such movement the played record is inclined above the receptacle so that it slides into the receptacle.

20. The combination with a phonograph turntable of a receptacle for played records below the level of the turntable, an oscillating record shifting member having a portion which enters the centre hole of a record, means whereby when a record is completed 40 the shifting member engages the record at the center hole of the record and slides it off the turntable and means whereby the record is caused to tilt upon leaving the turntable and slide downward into the receptacle.

21. The combination with a phonograph turntable and reproducer of a receptacle for played records below the level of the turntable, a pivoted record shifting member having an oscillating movement above the turntable and provided with a portion which enters the centre hole of a record, means whereby upon the completion of a record the shifting member engages the record at the center hole and slides it off the turntable and a 55 member adjacent the turntable for receiving the record and causing it to slide downward into the receptacle.

In witness whereof, I have hereunto set my hand this 8th day of August, 1923.

FRANK J. SEABOLT.
